UNITED STATES PATENT OFFICE.

ROBERT WILKINSON NEWTON, OF PROVIDENCE, RHODE ISLAND.

AUTOMATIC SPRINKLER.

1,290,298.

Specification of Letters Patent.

Patented Jan. 7, 1919.

Application filed March 8, 1918. Serial No. 221,220.

To all whom it may concern:

Be it known that I, ROBERT WILKINSON NEWTON, residing at Providence, in the county of Providence and State of Rhode Island, have invented a new and useful Improvement in Automatic Sprinklers, of which the following is a specification.

My invention has reference to an improvement in fire extinguishing devices and more particularly to an improvement in automatic sprinklers as used on automatic sprinkler systems.

The object of my invention is to improve the construction and operation of automatic sprinklers such as shown in United States Patent No. 514,161, patented to me February 6, 1894, to which reference is made, whereby corrosion in the valve seat and sticking or cohesion of the releasing element when in operation, are wholly eliminated.

Further objects of my invention are to reduce the cost of construction and improve the operation of automatic sprinklers, thereby producing a sprinkler that is more positively locked under normal conditions and more quickly released under fire conditions, than has heretofore been done.

My invention consists in the peculiar and novel construction of an automatic sprinkler, having details of construction, as will be more fully set forth hereinafter and claimed.

Figure 1 is a side view of my improved automatic sprinkler.

Fig. 2 is a longitudinal sectional view through the sprinkler taken on line 2.2 of Fig. 1.

Fig. 3 is an enlarged detail sectional view of the valve member showing the parts in a separated position.

Fig. 4 is an enlarged transverse sectional view taken on line 4.4 of Fig. 1 through the releasing device, and

Fig. 5 is an enlarged perspective view of the locking member.

In the drawings 6 indicates the body of an automatic sprinkler having the screw-threaded tubular shank 7, the yoke 8, and the arms 9,9 curving to the hub 10. A screw 11 is screw-threaded through the hub 10 and has the usual cone shaped inner end 12 and square outer end. A deflector 13 having the fingers 14,14 on its periphery, a cone shaped annular rib 15 and the holes 16,16 is secured to the hub 10 by a lock-nut 17. The inner end of the tubular shank 7 has a screw-threaded recess 18 and a detachable screw-

threaded valve seat 19 formed in two parts, is screwed into the recess 18. The valve seat 19 may be formed of glass or of a non-corrosive metal. A round box-shaped valve 20 is constructed to have a bottom 21 in which is a depression 22, a cover 23 which extends over the bottom and has a raised portion 24 on its top, a spring washer 25 in the box, a thin plate 26 which fits over the cover 23 and a thin washer 27 over the plate 26 and engaging the valve-seat 19. The plate 26 and washer 27 are gold plated on the surfaces that are in contact with each other, thereby eliminating corrosion between the washer and plate. Interposed between the end 12 of the screw 11 and the valve 20 is a bent valve support and releasing device 28, consisting of a thrust rod 29 having a rounded end engaging with the depression 22 in the valve 20, and a rounded end engaging with a cylindrical roll 30, a thrust rod 31 having a rounded end engaging with the roll 30 and an end in which is a depression engaging with the end 12 of the screw 11. The rods and roll are held in place by a shoe 32 shaped to hold the rods and roll and a plate 33. The shoe 32 has the extensions 34,34 in one of which are the slots 35,35 and in the other the holes 36,36. The plate 33 has the hooks 37,37 which hook through the slots 35,35 in the shoe, and the holes 36,36 which are alined with the holes 36,36 in the shoe, as shown in Fig. 4. A hollow tapered member 38 extends through and loosely fits in the holes 36,36 in the shoe and plate and has an enlarged head 39 under which is an asbestos washer 40. A collar 41 is secured to the end of the member 38 by a fusible rivet 42 through the member 38 and collar 41 and an asbestos washer 40 is placed between the collar 41 and the side extension 34. A locking member 43 is constructed to have a bent loop-shaped end 44 which goes around the shoe 32 at one end and over the plate 33 and has the end 45 which lies against the plate 33 and is fusibly secured to the releasing device 28 by a fusible rivet 46 as shown in Figs. 1 and 2.

By this construction the plate 33 acts as a lever to hold the thrust rods 29 and 31 in place in the shoe 32, so that they act as a solid strut between the valve 20 and the screw 11 and the plate is more securely held in place by the member 38 being as far as possible from the fulcrum of the lever or plate. The valve seat 19 being formed sep-

arate from the sprinkler allows the seat to be made of any non-corrosive material and the construction of the valve 20 is such that corrosion between the valve and valve seat 5 and corrosion of the valve spring is eliminated. The construction of the deflector 13 is such that a stream of water striking the deflector is broken up into larger drops, which is more effective in putting out fires, 10 than the spray from sprinklers as heretofore constructed. When the fusible rivets 42 and 46 are fused the pressure of the water on the valve 20 will cause the valve and all of the parts of the releasing device 28 to separate 15 and fall out of the sprinkler and the water will pass unobstructed to the deflector 13, from which it is distributed in large drops. In practice I find that this sprinkler will stand a heavy water pressure without 20 leaking or corrosion and at the same time is extremely sensitive in operation.

Having thus described my invention I claim as new.

1. In an automatic sprinkler, a valve supporting and releasing device consisting of a shoe, a plate over the shoe, thrust rods in the shoe and held in place by the plate, means for detachably and pivotally securing the plate to the shoe and means for fusibly 25 securing the plate to the shoe.

2. In an automatic sprinkler, a valve supporting and releasing device consisting of a shoe, thrust rods in the shoe and held in place by the plate, means for detachably and 35 pivotally securing the plate to the shoe at one side of the thrust rods and means for fusibly securing the plate to the shoe at the other side of the thrust rods.

3. In an automatic sprinkler, a valve supporting and releasing device consisting of 40 two thrust rods and an intermediate roll, a

shoe shaped to hold the thrust rods and roll, side extensions on the shoe, a plate over the thrust rods, roll and shoe, means for detachably hinging the plate to a side extension 45 and means for fusibly securing the plate to the opposite side extension.

4. In an automatic sprinkler, a valve supporting and releasing device consisting of thrust rods, a shoe shaped to hold the thrust 50 rods and having two side extensions one having a slot and the other having a hole, a plate over the thrust rods and shoe and having a hook in the slot in the side extension and a hole corresponding to the hole in the other side extension, a tapered member through the holes in the shoe and plate, and having an enlarged head, a collar on the opposite end of the locking member, and a fusible rivet through the locking member 55 and collar.

5. In an automatic sprinkler, a valve supporting and releasing device consisting of thrust rods, a shoe shaped to hold the thrust rods and having opposite side extensions one 60 of which has a slot and the other a hole, a plate over the thrust rods and shoe and having a hook in the slot and a hole corresponding to the hole in the shoe, a tapered member through the holes in the plate and shoe and 65 having an enlarged head, an asbestos washer under the head, a collar on the end of the tapered member, an asbestos washer intermediate the collar and the shoe extension, a fusible metal rivet through the tapered member and collar, a member having a bent loop-shaped end over the shoe and plate and an end secured by a fusible metal rivet to the 70 valve supporting and releasing device.

In testimony whereof I have signed my 80 name to this specification.

ROBERT WILKINSON NEWTON.
